C. B. LONGLEY,
PIPE COVERING,
APPLICATION FILED NOV. 22, 1916.

1,251,393.

Patented Dec. 25, 1917.

UNITED STATES PATENT OFFICE.

CLIFFORD B. LONGLEY, OF DETROIT, MICHIGAN.

PIPE-COVERING.

1,251,393.

Specification of Letters Patent. Patented Dec. 25, 1917.

Application filed November 22, 1916. Serial No. 132,866.

To all whom it may concern:

Be it known that I, CLIFFORD B. LONGLEY, a citizen of the United States, residing at Detroit, in the county of Wayne and State 5 of Michigan, have invented or discovered certain new and useful Improvements in Pipe-Coverings, of which the following is a specification, reference being had therein to the accompanying drawings.

10 This invention relates to heat insulating coverings or jackets for steam and other pipes, and has for its general object the provision of a covering of this character of maximum insulating efficiency which may 15 be manufactured at a minimum labor cost.

The foregoing and other objects of the invention, together with means whereby the same may be carried into effect, will best be understood from the following description 20 of one form or embodiment thereof illustrated in the accompanying drawing. It will be understood, however, that the particular construction described and shown has been chosen for illustrative purposes merely, 25 and that the invention, as defined by the claims hereunto appended, may be otherwise practised without departing from the spirit and scope thereof.

In said drawing:—

30 Figure 1 is an elevation, partly broken away, and

Fig. 2 is a section on the line 2—2, Fig. 1.

Referring to the drawings, 10 denotes a steam or other pipe inclosed by a jacket or 35 covering comprising a plurality of tubes 11, 12, 13 and 14 between which are interposed spacing strips 15. Each of the tubes 11, 12, 13 and 14 consists of one or more strips of insulating material, preferably 40 sheet asbestos, spirally wound with the adjacent edges of the spirals of each strip abutted, so as to constitute a continuous or unbroken tube. As herein shown the intermediate tubes 12 and 13 are composed of a 45 single strip each, while the innermost and outermost tubes 11 and 14, adjacent the pipe 10 and at the exterior of the jacket, respectively, are each composed of two strips *a* and *b*, wound one over the other in such a

50 manner that the abutting edges of one strip are offset with respect to those of the other. Preferably the arrangement is such that the abutting edges of one strip occupy a position about midway of the width of the other strip. This arrangement of the strips *a* and 55 *b* will break or offset the joints between the

two strips forming the said innermost and outermost tubes 11 and 14 so as to afford the greatest possible strength to these double-strip tubes.

The spacing strips 15 are also composed of insulating material, preferably wool or asbestos felt, and are also spirally wound. As herein shown a plurality of spacing strips 15 are interposed between each pair 60 of adjacent tubes, the spirals of the several strips 15 being separated or spaced from one another so as to form dead air spaces 16 between the strips and between the tubes.

The covering above described may be conveniently manufactured by means of a tube winding machine of any suitable or well-known form, by winding the tubes and spacing strips alternately in superposed relation upon a suitable mandrel. This winding may be accomplished by applying the strips one at a time or by feeding all or a plurality of the strips to the mandrel simultaneously at different points or from different directions, thereby reducing the number 70 of operations necessary in the manufacture of the tubes and even making it possible to form the completed tube at a single operation. After the desired number of layers 75 have been thus applied the completed jacket 80 may be split longitudinally and removed from the mandrel, and thereafter placed in position about the pipe to be jacketed and inclosed by a covering of canvas in the usual manner.

The angle at which the strips constituting the tubes 11, 12, 13 and 14 are wound is determined by the width of the strips and the diameter of the mandrel, said angle and width being in such relation to one another 90 and to said mandrel as to cause the edges of said strip to abut, as above described. The spacing strips 15 are, of course, narrower than the strips last mentioned, are preferably arranged parallel to each other in the 95 same layer, being wound at the same angle as the abutted strips, and are of a number determined by the desired distance between them, their own width, and the width of the 100 abutted strips.

105 It will be seen that the dead air spaces 16 coöperate with the tubes and spacing strips, both of which are composed of insulating material, to increase the insulating effect of said tubes and strips, thereby 110 greatly adding to the efficiency of the covering as a whole. It will also be seen that,

by reason of the spiral winding of all of the parts of the covering, said covering may be manufactured at a labor cost slightly if any greater than that of making the ordinary cardboard tube, thereby materially decreasing the cost of the complete article, it being well known that in the processes heretofore employed for making pipe insulations the labor involved constitutes about half the entire cost of manufacture. Furthermore the spiral method of construction gives greater structural strength than is found in the form of pipe insulation now commonly employed.

15 Having thus described my invention I claim and desire to secure by Letters Patent:

1. An insulating pipe covering comprising a plurality of tubes each consisting of spirally wound strips of material with the edges of the spirals abutted, and a plurality of parallel, spirally wound spacing strips interposed between said tubes, the spirals of said spacing strips being separated from each other so as to form dead air spaces between said tubes.
2. An insulating pipe covering comprising a plurality of tubes consisting of spirally wound strips of asbestos with the edges of the spirals abutted, and a plurality of parallel, spirally wound felt spacing strips interposed between said tubes, the spirals of said spacing strips being separated from each other so as to form dead air spaces between said tubes.
3. An insulating pipe covering comprising a plurality of tubes composed of spirally

wound strips of insulating material, the strips being of such width that when wound at a definite angle the edges of the spiral strips will be abutted, and a plurality of 40 spirally wound and relatively narrow, parallel spacing strips interposed between said tubes, the innermost and outermost of said tubes each comprising two spirally wound strips with abutted edges and one superposed on the other, with the joints of one strip offset with reference to the joints of the other.

4. The herein described method of forming insulating pipe jackets which consists in 50 spirally winding upon a suitable mandrel a plurality of superimposed layers, each composed of one or more strips of insulating material, the strips of certain of said layers being of such width that when wound at a 55 definite angle, which is determinate upon the width of the strip and the diameter of the mandrel, the edges of the spiral strips will be abutted, and the intermediate layers being a plurality of narrower strips wound spirally at the same angle and parallel to 60 each other in the same layer, the number of these strips being determined by the distance between them and their own width in the limits set by the width of the strips 65 forming the spiral layer with abutting edges, substantially as described.

In testimony whereof I affix my signature.

CLIFFORD B. LONGLEY.

Witness:

CHARLES R. ROBERTSON.
